W. T. SMITH

PUMP

Filed April 2, 1927

UNITED STATES PATENT OFFICE.

WALTER T. SMITH, OF GALVESTON, TEXAS.

PUMP.

Application filed April 2, 1927. Serial No. 180,523.

This invention relates to pumps, more particularly to pump impellers or runners used in connection more particularly with hydraulic dredging operations.

Heretofore it has been quite usual to pump up the water and solid matter into the bins of sea-going barges or dredges and allow the solid matter to settle out. This procedure involves considerable delay in settling out process. The broad object of this invention is to provide a pump having such construction that in the pumping operation the liquid will be mostly separated from the solid matter, the liquid being discharged from one outlet and the solid or semi-solid matter being discharged through another outlet and thence into a suitable bin or storage section.

Further objects are to provide a novel runner or impeller for drawing in the material to be acted upon, separating it, and forcing it out in its separated state; to provide a cheap readily renewable screen element; to provide simple means on the runner for confining the screen radially and causing it to turn with and, as part of, the runner or impeller; to provide a runner or impeller comprising impeller blades and a circumferentially arranged straining means disposed at an interval from the path of travel of the radially outer ends of said blades to constitute an inner annular chamber, in combination with a casing in which said runner is mounted, said casing having a discharge outlet communicating with said inner chamber and having its inner peripheral face arranged at an interval from said straining means to provide an outer annular chamber between said inner face and said straining element, said outer chamber being adapted to receive liquid forced through said straining element and said casing being formed with a separate discharge outlet communicating with said outer chamber, whereby the materials in said annular chambers will be discharged through separate outlets in their separated state; to provide a runner comprising blades, a straining element and means for confining said straining element radially so as to hold it to form and cause it to rotate as a part of said runner, in combination with a casing in which said runner is arranged, said casing having a removable part normally preventing axial movement of said strainer element while permitting easy access there-

to and removal thereof in an axial direction; to provide a construction of runner blades curvilinear in shape with their convex faces presented in the direction of rotation to force the materials outward radially and create a strong pressure to force the materials, as separated, under pressure out of their separate outlets without other means of propulsion; to provide a readily removable and renewable liner element provided with a relatively fixed spade element projecting, as assembled, into the inner annular chamber, preferably the upper portion thereof, and registering with the discharge thereof to aid in discharging the material therefrom and to act as a scraper in keeping the strainer element unobstructed or clean; and to otherwise improve and simplify the construction and operation, all of which objects, among others, are accomplished by the construction, combination and arrangement of parts, all as hereinafter set forth and described.

In the accompanying drawings in which only several of the possible embodiments of my invention are shown and described for the purpose of illustrating my invention and the practice thereof as by law required, but with no intention of being limited thereto, it being recognized by me that it is capable of embodiment in a number of other forms:

Fig. 1 represents a sectional view of a device embodying my invention taken on line 1-1 of Fig. 2;

Fig. 2 represents a sectional view thereof taken at right angles to Fig. 1; on line 2-2 of said figure;

Fig. 3 represents a fragmentary sectional view of a modified strainer construction having two nesting cylinders with an intervening layer of gunny sacking or other suitable straining material; and

Figure 4 represents a detail fragmentary view on line 4-4 of Fig. 2, looking in the direction of the arrow, omitting, however, all parts except the liner 2 and the spade 3 shown integral therewith.

Referring now in detail to the drawings, the casing comprises an annular member A, side plates B and B' secured to the member A by bolts C or in any other usual manner. Side plate B is centrally bored and provided with a bushing E which receives packing F packed by the usual gland-nut G. The side plate B' is provided with a central inlet H and with a discharge port I and the periph-

eral member A is provided with a liquid discharge port D, and base I. The runner or impeller shaft 5 extends through the central bore of plate B and has its inner end 6 reduced and preferably externally screw threaded to receive the preferably internally screw threaded hub 7 of the runner comprising preferably, an imperforate disk 8 having the preferably equi-distantly spaced strainer holding fingers 11 extending from its edge axially toward the intake side of the casing, and curvilinearly disposed vanes 9 having their convex faces presented in the direction of rotation indicated by the arrow, 15 Fig. 2, said vanes preferably having end faces 10 arcuate in shape struck on the circle described by said ends, and said vanes extending equally to a point radially at a distance from the strainer to leave an annular 20 space between the strainer 12 and the path of travel of the ends 10 of said vanes 9 which, however, turn together with said strainer 12, practically as a single part. 25 The runner assemblage as arranged in the casing is spaced from the plate B by removable liner 4 and from the plate B' by removable liner 2 and the strainer 12 is disposed at an interval from the inner face of the element A, said interval being substantially the same as the interval between the 30 ends 10 of the runner vanes 9 and the strainer 12, thus in effect constituting an inner and an outer annular chamber concentric with each other and with the axis of the runner or impeller, the outer chamber discharging its liquid contents through the discharge D and the inner chamber discharging through the opening 1.

The liner 2 is provided with a preferably 40 integral projection or spade 3 having a curved and radially outwardly inclined inner face and is so formed and positioned as to register with one side of, and extend into, the opening 1 and as thus positioned and 45 arranged its inner portion extends into the inner annular chamber between the strainer 12 and the runner vanes 9 for a distance nearly the actual width of said chamber and so as to be in, or almost in, contact by its 50 radially outer face with said strainer 12 so as to intercept any solid or semi-solid material in said chamber as the same is carried around by said strainer 12 and to divert such material to said discharge opening, thus serving to intercept said material 55 for purpose of discharge and also to keep said strainer 12 clear.

The strainer 12 is preferably an endless 60 perforated band of sheet metal of suitable thickness having fine perforations and which may have imperforate parts at the points corresponding to the location of the fingers 10 and will be of a size to just fit tightly between said equi-distantly spaced fingers 65 10, the fit being so tight as to prevent rela-

tive movement between said strainer 12 and fingers 10.

The operation may be briefly stated as follows; the impeller rotating in the direction of the arrow, Fig. 2, draws the water and solids in through the opening H and forces the water through the screen into the outer chamber and the solid matter against the screen and creates a pressure that forces the water in the outer chamber outward through discharge D and also forces the solid and semi-solid matter outward through discharge 1, this latter operation being facilitated by the spade 3.

The liners 4 and 2 may be held in place by 80 screws 13 extending through their respective plates B and B' as illustrated in Figure 1, or by any usual and suitable means now commonly employed for that, or similar purposes.

The discharge 1 communicating with the inner chamber may be, and preferably will be, defined by a removable liner or wear bushing 14, held in place in any suitable manner, as by screws 15, and the intake 90 opening H may similarly be, and preferably will be, defined by a removable liner or wear bushing or lip 16, which extends slightly beyond the inner face of the liner 2 and which may be similarly held in place by 95 similar screws 15.

The supply and discharge pipes not shown may be connected with their inlet and discharge ports in any suitable manner.

While it is preferred that the runner 100 should have an imperforate part such as disc 8, this is not essential, but it is important that some means, rotating with the vanes 9, be provided for maintaining the strainer 12 in proper position with relation 105 to the ends of said vanes 9 and the member A so as to provide the inner annular chamber for the solid or semi-solid matter and the concentric outer annular chamber for the liquids, substantially as above described. 110

In the modified form in Figure 3 the construction and operation are in all respects the same as in the preferred form above described, except that instead of the strainer 12 a composite screen comprising an annular outer perforated band 12^a and a similar band 12^b nesting in said outer band 12^a and an intervening layer of gunny sacking or other suitable material 12^c, is substituted for the strainer 12, the perforations in bands 115 12^a and 12^b being considerably larger, or several times larger, than the perforations in the strainer 12.

In both forms illustrated the runner will 125 preferably have a disc 8' on its intake end, said disc 8' being, of course, formed with a central intake opening concentric with the intake opening in the end plate B' and of such size as to receive, and be centered by the inner end of the intake lining or remov- 130

able lip 16, as shown in Figure 1, and the runner as a whole, comprising the discs 8 and 8' the vanes 9 and the fingers 11 will preferably be, operatively considered, an integral piece, and may be a casting.

Having thus described my invention, what I claim as new and desire to secure by Letters Patent is:

1. A pump casing having an intake port and two independent discharge ports, in combination with a rotary impeller arranged in said casing, and means for rotating said impeller, said impeller comprising impeller vanes, and an annular strainer element immovable with relation to said blades and spaced between the radially outer ends thereof and the opposed face of said casing, whereby two concentric annular chambers are provided, the inner chamber discharging through one of said discharge ports and the outer chamber discharging through the other of said discharge ports.

2. A pump casing having an intake port and two independent discharge ports, in combination with a rotary impeller arranged in said casing, and means for rotating said impeller, said impeller comprising impeller vanes, and an annular strainer element immovable with relation to said blades and arranged substantially equi-distantly, in a radial direction, between the radially outer ends thereof and the opposed face of said casing, whereby two concentric annular chambers are provided, the inner chamber discharging through one of said discharge ports and the outer chamber discharging through the other of said discharge ports.

3. A pump casing having an intake port and two independent discharge ports, in combination with a rotary impeller arranged in said casing, and means for rotating said impeller, said impeller comprising impeller vanes, fingers carried by said impeller and extending at points about the axis thereof axially toward the intake side of said casing, and an annular strainer element fitting between said fingers and held substantially immovable with relation to said blades and as thus mounted being arranged between the radially outer ends thereof and the opposed face of said casing, whereby two concentric annular chambers are provided, the inner chamber discharging through one of said discharge ports and the outer chamber discharging through the other of said discharge ports.

4. A pump casing having an intake port and two independent discharge ports, in combination with a rotary impeller arranged in said casing, and means for rotating said impeller, said impeller comprising curvilinearly disposed impeller vanes, having their convex faces presented in the direction of rotation of said impeller, and an annular strainer element immovable with relation to

said blades and spaced between the radially outer ends thereof and the opposed face of said casing, whereby two concentric annular chambers are provided, the inner chamber discharging through one of said discharge ports and the other chamber discharging through the other of said discharge ports.

5. A pump casing having an intake port and two independent discharge ports, in combination with a rotary impeller arranged in said casing, and means for rotating said impeller, said impeller comprising curvilinearly disposed impeller vanes having their convex faces presented in the direction of rotation of said impeller, and an annular strainer element immovable with relation to said blades and arranged substantially equi-distantly, in a radial direction, between the radially outer ends thereof and the opposed face of said casing, whereby two concentric annular chambers are provided, the inner chamber discharging through one of said discharge ports and the outer chamber discharging through the other of said discharge ports.

6. A pump casing having an intake port and two independent discharge ports, in combination with a rotary impeller arranged in said casing, and means for rotating said impeller, said impeller comprising impeller vanes, an annular strainer element immovable with relation to said blades and spaced between the radially outer ends thereof and the opposed face of said casing, whereby two concentric annular chambers are provided, the inner chamber discharging through one of said discharge ports and the outer chamber discharging through the other of said discharge ports, and a spade element held immovable with relation to said casing, and registering with one of said discharge ports and extending axially into said inner annular chamber in proximity to said strainer element to scrape the more solid matter therefrom and to direct the solid and semi-solid matter in said inner chamber outward through its co-operating discharge port.

7. A pump casing having an intake port, a radially outer discharge port and a radially inner discharge port in combination with a rotary impeller arranged in said casing, and means for rotating said impeller, said impeller comprising impeller vanes, an annular strainer element immovable with relation to said blades and spaced between the radially outer ends thereof and the opposed face of said casing, whereby two concentric annular chambers are provided, the inner chamber discharging solid and semi-solid material through the radially inner discharge port and the outer chamber discharging fluids through the radially outer discharge port, a normally fixed removable liner plate, and a spade carried by said liner plate, immovable with relation thereto

registering with said radially inner discharge port and extending in an axial direction into said inner annular chamber in close proximity to the radially inner face of 5 said strainer element.

8. A rotary pump impeller comprising vanes, a portion turning with said vanes, immovable with relation thereto and extending to at least a plurality of diametrically opposite points radially beyond the radially outer ends of said vanes, parts extending from said diametrically opposite points, and an endless band perforated sheet metal strainer held by said parts so as to extend 15 concentrically about the axis of said impeller and so as to turn with said vanes.

9. A rotary pump impeller comprising vanes, a disc turning with said vanes and extending radially beyond the radially outer 20 ends of said vanes, fingers extending at equidistant points about the edge of said disc in an axial direction toward said vanes, and an endless band perforated sheet metal strainer applied in an axial direction between said 25 fingers and of such diameter as to be held tightly thereby to turn therewith.

10. A rotary pump impeller comprising vanes, a portion turning with said vanes, immovable with relation thereto and extending 30 to at least a plurality of diametrically

opposite points radially beyond the radially outer ends of said vanes, and an annular strainer element mounted at such diametrically opposite points on said portion so as to extend concentrically about the axis of 35 said impeller and held by said portion to turn with said vanes.

11. A removable liner plate for a pump casing, said plate being formed with a lateral discharge opening, and a spade element 40 immovable with relation to said plate projecting laterally therefrom away from, and registering with, said discharge opening.

12. A removable liner plate for a pump casing, said plate being formed with a lateral discharge opening, and an integral spade element immovable with relation to 45 said plate projecting laterally therefrom away from, and registering with, said discharge opening.

13. A removable liner plate for a pump casing, said plate being formed with an integral spade element adapted, in the arranged relation of said liner plate, to project into the interior of said casing. 50

In testimony whereof, I have signed my name to this specification at New Orleans, Louisiana, this 22 day of March, 1927.

WALTER T. SMITH.
